UNITED STATES PATENT OFFICE.

LEMUEL MCKINNON, OF SALT LAKE CITY, UTAH.

TIRE.

1,176,073.

Specification of Letters Patent. Patented Mar. 21, 1916.

Application filed March 26, 1915. Serial No. 17,214.

To all whom it may concern:

Be it known that I, LEMUEL MCKINNON, a citizen of the United States, residing at Salt Lake City, in the county of Salt Lake and State of Utah, have invented a new and useful Tire, of which the following is a specification.

The device forming the subject matter of this application is a resilient tire and the invention aims primarily, to provide a novel combination of resilient elements which co-operate to give the necessary spring effect to the tire.

It is within the scope of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings: Figure 1 shows the invention in vertical circumferential section, parts appearing in elevation; Fig. 2 is a cross section taken strictly on the line 2-2 of Fig. 1, distant parts being omitted; Fig. 3 is a fragmental top plan, parts being successively broken away and sectioned; Fig. 4 is a fragmental top plan showing the connected ends of the tightening band; Fig. 5 is a fragmental longitudinal section showing a modified means for connecting the ends of the band.

In carrying out the present invention there is provided a rim 1 equipped with any desired means for holding a tire casing 3 which, as usual, is divided along its median line, adjacent the rim 1. In the present instance, but not of necessity, the rim 1 is equipped with clencher flanges 2 engaging the casing 3. Located within the casing 3 and conforming to the interior cross section of the casing is a tubular lining 4 which may be made of canvas.

Disposed within the lining 4 are a plurality of resilient blocks 5, spaced apart circumferentially of the tire. The blocks 5 may be made of rubber or some composition having the desired resiliency. The blocks 5 are disposed adjacent the tread portion of the lining 4 and conform closely to the interior contour of the lining 4 throughout a portion of the cross section thereof, the blocks preferably being in the form of segments of circles in cross section. The end faces 6 of the blocks 5 are disposed at an acute angle to the median plane of the tire, as indicated clearly in Fig. 3, so that the weight may come onto one block before it is entirely off an adjoining block.

The resilient blocks 5 rest on a resilient, divided band, the same ordinarily being fashioned out of a plurality of longitudinally extended strips of resilient wood, externally extended circumferentially of the tire, the ends of the successive strips being disposed in break joint relation. The strips 7 which make up the resilient band may be connected together by means of rivets 8 or in any other suitable manner. The resilient blocks 5 fill closely, transversely of the tire, the space existing between the outer face of the band and the inner face of the lining 4.

The band which is composed of the strips 7 is united at its ends by angle members, one end of the strip being recessed to receive the circumferential arm 9 of one angle member, the radial arm of which is denoted by the numeral 10. This angle member and another angle member to be described hereinafter are connected with the respective ends of the band by means of rivets 11 or other securing elements adapted to a like purpose. The other angle member comprises a circumferential arm 12 and a radial arm 14, the arm 12 being equipped with a circumferential tongue 15 bridging the space between the arms 10 and 14 of the respective angle members, and slidably received in a recess 16 formed in the arm 9 of one angle member. The inwardly projecting arms 10 and 14 of the angle members may be united adjustably by any suitable means, such as one or more screws 17 journaled for rotation in the arm 14 and threaded into the arm 10.

One means for securing the resilient blocks 5 to the resilient band composed of the strips 7 is a lacing cord 18 passed spirally through openings in the blocks and 5 in the band, as will be obvious when Fig. 3 is compared with Fig. 1. Disposed within the contour of the lining 4 is an inflatable tube 19 provided with a plurality of circumferentially spaced, outwardly projecting 10 cells 20, the tube proper 19 and each cell 20 being of a size to fill the cross sectional area defined by a portion of the lining 4 and the band composed of the strips 7. The tube 19 and its cells 20 are inflated by means of a 15 valve tube 21 extended inwardly through the rim 1 as will be understood best from Fig. 1 of the drawings.

The invention includes a circumferential tightening band 22 which may be of any desired form. The band 22 may be in the form 20 of a canvas tube flattened down so that its opposed portions are in contact, Fig. 1 being referred to for a clear understanding of this detail. A means is provided for drawing 25 the extremities of the tightening band 22 together, and with this end in view there is provided a block 23 preferably of metal and conforming approximately to the cross section 30 of the tightening band 22. The block or strip 23 includes a tongue 24 passing between the constituent layers of the band 22 and held thereto by means of rivets 25 or the like. The other end of the tightening band 22 is provided with a strip or block 26 including a tongue 27 held in place by rivets 28 as before. A pair of screws 29 are held 35 at one end in the strip 26 and are adapted to move longitudinally in slots 30 formed in the strip or block 23. The slots 30 are provided with transverse extensions 31, receiving 40 for rotation but against movement circumferentially of the tire, worm wheels 32 operated by means of a radial worm 33 provided with an exposed wrench head 34, the 45 worm 33 projecting through an opening 35 in the tire 3. In order to prevent the worm from moving toward the tread of the tire when the worm is rotated, a thrust plate 36 is attached to the block or strip 23 and engages 50 one end of the worm.

In practical operation, the tightening band 22 may be drawn up by actuating the worm 33, the same rotating the worm wheels 32 which, being threaded upon the screws 55 29, will serve to tighten up the band 22. At this point it may be noted that the valve tube 21 lies between the strips 23 and 26, and preferably is disposed between the screws 29 as will be understood when Fig. 60 1 is compared with Fig. 4. The tube 19 may be inflated readily, the tube and its cells 20 being expanded so that the latter bear against the band composed of the strips 7. Owing to the fact that the cells 20 are

spaced apart circumferentially of the tire, 65 the band composed of the strips 7 is permitted to give to some extent between the cells. Further, owing to the fact that the resilient blocks 5 are spaced apart circumferentially of the tire, the resiliency of the 70 latter is enhanced, but in this connection it is to be observed that the tire will operate without any bumping effect, owing to the fact that, as shown in Fig. 3, the blocks 5 are beveled at 6 so that they overlap, circumferentially of the device. 75

In the modification shown in Fig. 5, the inner band strips are shown at 100, the numeral 101 indicating the outer band strips, and the intermediate band strips 80 being designated by the reference character 102. An angle member 103 abuts against the end of the band strip 101 and an angle member 104 abuts against the end of the band strip 100. The angle member 103 comprises a flange 105 extended across the ends of the intermediate band strips 102 and overlapped upon the end flange 109 of the angle member 104. The angle members 103 and 104 are secured to the intermediate strips 90 102 by means of rivets 108 or the like. Interposed between the end flanges 105 of the respective angle members 103 is a wedge 106 held in place by a bolt 107 passing through the flanges 105 and 109. The angle members and the wedge may be fashioned from any desired material, but copper will be 95 found satisfactory.

Having thus described the invention, what is claimed is:—

1. In a device of the class described, a casing; an inflatable tube located within the casing and provided with circumferentially spaced, outwardly projecting cells; and resilient means interposed between the cells 105 and the tread portion of the casing.

2. In a device of the class described, a casing; an inflatable tube within the casing and provided with circumferentially spaced, outwardly projecting cells; a resilient band extended circumferentially of the wheel and coacting with the cells; and spacing means interposed between the band and the tread portion of the casing.

3. In a device of the class described, a 115 casing; an inflatable tube located within the casing and provided with circumferentially spaced, outwardly extended cells; a resilient band extended circumferentially of the casing and coacting with the cells; and spaced 120 resilient blocks interposed between the band and the tread portion of the casing.

4. In a device of the class described, a casing; an inflatable tube located within the casing and provided with circumferentially 125 spaced, outwardly extended cells; a resilient band extended circumferentially of the casing and coacting with the cells; and resilient

blocks interposed between the band and the tread portion of the casing, the end faces of the blocks being spaced apart, and the end faces of the blocks being acutely disposed with respect to the median plane of the casing.

In testimony that I claim the foregoing

as my own, I have hereto affixed my signature in the presence of two witnesses.

LEMUEL McKINNON.
